UNITED STATES PATENT OFFICE.

WALTER MAKI, OF DETROIT, MICHIGAN.

SLED.

Application filed February 23, 1922. Serial No. 538,641.

To all whom it may concern:

Be it known that I, WALTER MAKI, a citizen of the United States, residing at Detroit, in the county of Wayne and State of Michigan, have invented certain new and useful improvements in Sleds, of which the following is a specification.

This invention relates to improvements in sleds and more particularly to the class of kicking sleds. The sled is propelled by one person standing with one foot on one runner and kicking the sled forward holding to the handle of the sled meanwhile; another person may occupy the seat of the sled. Another object is to provide a sled of this type that can be folded up to occupy the minimum space when not in use, when in storage or for shipping purposes. A further object is to provide a sled of this type that is of simple construction, durable and efficient in use.

With the foregoing and other objects in view the invention consists in the combination and arrangement of parts to be herein-
after fully described, pointed out in the appended claim and illustrated in the accompanying drawing which forms a part of this application and in which—

Fig. 1 is a view of my sled in side elevation, the dotted lines denoting the position of the folding parts when not in use.

Fig. 2 is a top plan view of the sled.

Fig. 3 is a fragmentary plan view of the sled.

Fig. 4 is an enlarged fragmentary view showing the means for retaining the seat rigidly in position in the operative position of the sled.

Fig. 5 is a cross section on line 5—5 of Fig. 3.

Like reference characters denote corresponding parts throughout the several views.

The reference numeral 1 denotes the runners having their front ends 2 upturned. To the runners I secure a pair of ears 3 to which a pair of standards 4 are pivotally connected by the pins 5, said standards being connected at their upper ends by the handle

6. Pivotally secured to the upturned ends of the runners 1 is a frame 7 the sides of which converge from the upturned runner ends and cross beneath the seat 8 that they

support, the ends of the frame 7 being formed with the notches 9 for engagement with the buttons 10 carried by the standards 4 whereby said frame 7 is supported in operative position.

A substantially U-shaped member 11 has its ends secured by the bar 12 to the standards 4, the base of said member being adapted for disposal upon the seat 8, in the operative position of the same, and being releasably secured thereto by the spring fingers 13 carried by the seat, said seat being secured to the frame 7 by the staples 14, the sides of said members serving as arms for the seat in operative position. Brace bars 15 for the standards 4 connect the lower ends of the same and the said bar 12 and a spring arm 16 carried by the bar bears upon the seat 8 in the operative position of the same to prevent it, together with the frame 7, from becoming accidentally disengaged from the buttons 10.

In Fig. 1 in full lines and in Fig. 2 the sled is shown in assembled or operative position. To move it to the position shown in dotted lines in Fig. 1 the member 11 is disengaged from the spring fingers 13, the notched ends of the frame 7 disengaged from the buttons 10 and the standards and frame 7 then permitted to drop to the position shown. These parts may now be tied or strapped to the runners and the sled is ready for storage or for shipping.

What is claimed is:

In a sled, runners, standards pivotally carried thereby, a cross bar connecting said standards, a frame pivoted to the ends of said standards and adapted for releasable supporting engagement with said standards, a seat carried by said frame, and means carried by said cross bar for engagement with opposite ends of said seat whereby the same and said frame are retained in operative position, said means comprising a spring arm terminally bearing upon the seat.

In testimony that I claim the foregoing as my own I have hereto affixed my signature in the presence of two subscribing witnesses.

WALTER MAKI.
